(57) **CLAIM**

The ornamental design for a front combination lamp, as shown and described.

DESCRIPTION

FIG. 1 is a front view of a front combination lamp showing my new design.

FIG. 2 is a rear view thereof.

FIG. 3 is a plan view thereof.

FIG. 4 is a bottom view thereof.

FIG. 5 is a right side view thereof.

FIG. 6 is a left side view thereof.

FIG. 7 is a perspective view thereof as seen from the left front side; and,

FIG. 8 is a perspective view thereof as seen from the left rear side.

The broken line showing of the rear of the front combination lamp is for illustrative purposes only and forms no part of the claimed design.
